ELECTRICAL CONNECTOR

James C. Macy, New Cumberland, Pa., assignor
to Aircraft-Marine Products Inc., Harrisburg,
Pa., a corporation of New Jersey

Application November 27, 1945, Serial No. 631,031

6 Claims. (Cl. 173—328)

1

This invention relates to multiple connectors, particularly to multiple connectors of the knife-disconnect type. It is a continuation-in-part of my application Serial No. 558,326, filed October 12, 1944.

As more fully disclosed in the copending application of William S. Watts, Serial No. 530,296, filed April 10, 1944, now Patent No. 2,478,143, and my own applications, particularly Serial No. 530,317, filed April 10, 1944, terminal connectors and multiple connectors of the knife-disconnect type have, as characteristic features, a blade part engageable between a similar blade part and cooperating clip of a counterpart terminal. These connectors are usually so constructed and the clips and blades so formed that when two such terminals are brought together at right angles with their blade portions face to face and are then swung into alignment, each blade makes a wiping pressure contact between the clip and the blade of the other terminal, while its clip, engaging the clip of the other terminal, holds against axial disengagement.

The present invention aims particularly to provide a multiple connector for use with conductors having terminal connectors of the aforementioned knife-disconnect type. The invention also has as one object the provision of a multiple connector which is economical of weight, material and space. The invention further aims to provide a multiple connector for use with conductors having terminal connectors of the knife-disconnect type which has its various counterpart connectors so arranged that when the various wires, or other members carrying the counterpart connectors, are engaged with the multiple connector, the entire assembly may be locked against disengagement by a cover which may serve not only to insulate and lock the connections but also to protect them against physical injury. An additional object resides in providing a multiple connector which readily may be combined with other similar multiple connectors to build up a range of sizes of connector units.

Other objects of the invention, to which reference has not been specifically made hereinabove, will be referred to hereinafter or will be apparent when the following description and claims are considered in connection with the accompanying drawings.

2

Although in this specification and the accompanying drawings I am showing and describing a particular example and various modifications thereof, it should be understood that these are not intended to be exhaustive nor limiting of the invention, but on the contrary are chosen and presented for purposes of illustration and in order to explain the principles of the invention and the practical employment of those principles in applying the invention to practical use, and thus so fully to instruct others skilled in this art that they will be enabled readily to modify and to select and substitute alternatives, each as may be best suited to the particular conditions of any given application or use.

In the drawings:

Figure 1 is a perspective view of a multiple connector embodying the invention;

Figure 2 is a sectional view taken longitudinally through the assembly of Figure 1;

Figure 3 is a sectional view taken along the line 3—3 of Figure 2;

Figure 4 is a perspective view of a spacer block which forms a part of the assembly of Figures 1 and 2;

Figure 5 is a sectional view through the block of Figure 4;

Figure 6 is a perspective view of a modified type of multiple connector;

Figure 7 is a sectional view taken along the line 7—7 of Figure 6;

Figure 8 is a sectional view taken along the line 8—8 of Figure 7;

Figure 9 is a plan view of a portion of a block similar to that shown in Figure 6 but fitted with various modified connectors;

Figure 10 is a sectional view taken along the line 10—10 of Figure 9;

Figure 11 is a perspective view of three connectors of the type shown in Figure 6 stacked one on top of another;

Figure 12 is a sectional view taken along the line 12—12 of Figure 11;

Figure 13 is a perspective view of a further modification of the invention;

Figure 14 is a plan view with parts broken away of the multiple connector of Figure 13;

Figure 15 is a sectional elevation taken along the broken line 15—15 of Figure 14;

Figure 16 is a sectional view taken along the line 16—16 of Figure 14;

Figure 17 is a view with parts broken away of another multiple connector embodying the invention;

Figure 18 is a longitudinal sectional view taken along the line 18—18 of Figure 17;

Figure 19 is an end view of the connector shown in Figure 17 with parts broken away;

Figure 20 is a sectional view taken along the line 20—20 of Figure 18; and

Figure 21 is a perspective view of an interconnector blade which forms a part of the multiple connector.

In Figure 1 a multiple connector assembly is indicated by the numeral 20 consisting of a spacer block 22 (see also Figure 4) and a pair of covers 24 and 26 (see also Figure 2). The connector assembly is shown interconnecting a plurality of electrical conductor wires W. Each wire W is provided with an electrical connector 28. Each connector 28 is of the knife-disconnect type previously referred to and includes a ferrule portion 30, a contact portion 32 having a blade 34, and a clip 36. Spacer block 22 is provided in the present embodiment with a series of radially arranged slots 38. An electrical interconnector blade 40 is positioned in each slot 38. Each blade 40 includes on each side of block 22 a shank 42 and a clip 44. As shown in Figures 2 and 5, each blade 42 is provided with a pair of spaced nubs 46 which prevent longitudinal movement of the blade in its slot 38. Each contact portion 32 includes an offset 48 in its blade 34. This offset serves the dual purpose of promoting a solid engagement between connector 28 and blade 40 and keeping the two connector elements in space saving alignment all as described and claimed in my copending application Serial No. 530,317 above-mentioned.

The connector 28 can be disengaged from interconnector blade 40 only when moved to the relationship illustrated in Figure 5, where the axis of connector 28 is substantially at right angles with respect to the axis of blade 40. In the relationship shown in Figure 2, the connectors and interconnectors cannot be separated. Thus, while covers 24 and 26 remain fitted to block 22, the wires W cannot become disengaged and the circuits therethrough must accordingly remain positively established.

It will be seen in the present embodiment that the invention is in part an improvement upon the invention of Harry B. White, Patent No. 2,383,926, and Stephen N. Buchanan, Patent No. 2,383,909. When the covers are backed away from block 22 to the positions shown in dotted lines in Figure 2 the various wires are unlocked and any or all may be disconnected or rearranged at will. And the connector block may be mounted in any sort of panel and thus serve to facilitate making and keeping connections between one side of the panel and the other. It will be appreciated that, where air pressure differentials must be maintained between the respective sides of the panel upon which the connector block is mounted, the various interconnector blades 40 may advantageously be molded directly in block 22, as is disclosed more fully hereinafter in connection with the description of Figures 17-20, thus eliminating slots 38 and presenting an imperforate surface across both faces of the block. Alternatively the slots may be sealed after assembly.

In Figures 6 through 8 the invention is shown as incorporated in a connector assembly which includes as a principal element thereof a rectangular spacer block 22a instead of the panel-

type block 22 of the previous embodiment. In this form the connector assembly has utility as an ordinary tie point or terminal block where, for the sake of convenience, the connectors of certain related circuits are grouped. In the present embodiment no interconnector blade nor third part, such as the previous blade 40, is required for the reason that each of the wires Wa is provided with a modified form of terminal. Each terminal has a ferrule portion 30a and an elongated contact portion 32a including a blade 34a and clip 36a. The contact portion 32a extends between nub 46a and offset 48a and corresponds in length to the width of the rectangular block 22a so that it fits nicely into slot 38a in the block. Cover 24a locks the various contact portions 32a in position in slots 38a so that wires Wa cannot be separated from the connector block except when cover 24a is removed. The blades 34a and clips 36a remain exposed in this form. Wires Wb carry terminals having ferrule portions 30b, blades 34b and clips 36b which may readily be connected to or disconnected from the corresponding parts of the fixed electrical connectors.

Block 22a is provided at each end with a shoudered hole 50 having a threaded portion 52 for reception of a screw post 54. A machine screw 56 is threaded into post 54 to hold cover 24a securely upon block 22a. This cover securing means has particular utility in connection with the embodiment shown in Figures 11 and 12.

Figure 9 shows a spacer block 122a on the left hand side of which appear electrical conductors Wa1, Wa2 and Wa3. Conductor Wa1 is substantially identical with conductors Wa of Figure 6. It is provided with a ferrule portion 130a, a blade 134a, a nub 146a and an offset 148a. Nub 146a and offset 148a are spaced apart by an amount equal to the width of block 122a so that the connector cannot move lengthwise in its slot. Nub 146a is held tightly in engagement with face 246a of the block and shoulder 148a is held tightly in engagement with face 245a of the block. When a connection is made the clips 136a and 36b are tightly jammed between nub 146a and an offset 48b so that lengthwise relative movement between the two connectors is impossible. Thus a good electrical contact results. Conductor Wa2 is provided with a connector having an offset 248a

but it does not include a nub corresponding to the nub 146a. Figure 10 illustrates the manner in which the curved forward edge of clip 36b, when the clip is engaged with the clip of blade 234a, provides a camming action against block face 246a to lock blade 234a in its slot within block 122a and to jam the interfitting clips into good conducting relationship so that a tight mechanical connection exists all the way between shoulders 48b and 248b. Conductor Wa3 and its connector are similar to conductor Wa2 and its connector except for the provision of a nub 346a which interfits within a molded recess in slot 238a so that relative movement of the blade of the connector within slot 238a is not possible even when no blade 34b and clip 36b are interfitted with the connector. There is advantage, as pointed out in my earlier application Serial No. 530,317, in having a shoulder or nub, such as nubs 46a, 146a, etc., against which the curved forward edge of the clip can act to cam the connecting portions into an intimate pressure contact. The face of the spacer block may similarly be advantageously used as described in reference to conductors Wa2 and Wa3. In addition, a saving in space and materials results where the clip of

a connector is made to cam against the face of a spacer block instead of against a nub.

In Figures 11 and 12 a series of spacer blocks consisting of one block 22a and two blocks 22b and a cover 24a are shown secured together. The screw post 54, shown in Figure 7, is replaced by an extension screw post 58 (see Figure 12). Thus, with appropriate extension screw posts, any number of spacer blocks may be stacked and secured one on top of another simply by drilling out shoulder holes 59 to give the cylindrical configuration indicated at 59b. The distance between adjacent slots 38a should preferably be the same for each two adjacent pairs of slots so that the slots are equally spaced across the block. The distance between an end slot and the adjacent end of the block preferably should be different at opposite ends of the block so that when one block is placed on top of another block and turned end for end, the slots of the upper block will not be directly over the slots of the block immediately below. Thus the various rows of electrical connectors are staggered with respect to one another so that the connections and disconnections may more easily be made without disturbing adjacent wires.

The embodiment of Figures 13-16 differs from that of Figures 6-9 in that block 22c is approximately twice as wide as block 22a and is fitted with a pair of covers 24c and 26c so that the entire connector portions of wires Wc and Wd are fully covered. Thus wires Wc may be disconnected from the multiple connector assembly only when cover 24c is removed. Wires Wd may be removed from the assembly only when both covers 24c and 26c are removed. A plurality of spacer blocks may be stacked one on top of another as described in connection with the embodiment of Figures 11 and 12 (see Figure 16) although it will be appreciated that the stack must be partly separated when connections through any but the top block of the stack are to be altered. Corresponding parts are identified by means of corresponding reference numerals except for the change in reference letters suffixed.

Figures 17-21 illustrate a further embodiment similar in many respects to that of Figures 1-5. Again similar reference characters are used for similar parts with the exception of different reference-letter suffixes. Spacer block 22e comprises a slotted disc 60 and a retaining flange 62 tightly fitting therearound so that flange 62 serves to lock the interconnector blades 40e (see Figure 21) in radial slots 38e of disc 60. In addition a pair of cores 64 and 66 (see Figure 18) are permanently clamped together upon disc 60 by means of a rivet 68. Thus disc 60, cores 64 and 66, and rivet 68 in effect form an integral spacer block unit, and when blades 40e are fitted within slots 38e, retaining flange 62 may be frictionally forced upon the blade-carrying disc to form a solid assembly of disc, blades and cores. Such an assembly can be made to present a substantially imperforate barrier where pressure differentials are to exist on opposite faces of the connector unit. As shown in Figures 19 and 20, each of the covers 26e extends through 180°, instead of cylindrically as in the form of Figures 1-5, and the two covers 26e are clamped together by a pair of spring clips 70 (see Figure 19) which fasten upon flanges 72 and 73. The assembled covers 26e are prevented from slipping off of core 66 by means of a pair of annular ridges 74 and 76 (see Figure 18) which interfit with a pair of annular depressions 78 and 80 running around

core 66. The assembled covers 24e are similarly retained upon core 64. When it is desired to connect or disconnect a wire We, the appropriate cover 24e or 26e is removed by first removing 5 spring clips 70 so that the two half covers may be separated and removed thus giving access to connector portions of interconnector blade 40e. The embodiment of Figures 17-20 has advantage over that of Figures 1-5 in that the covers do not 10 have to be backed off along the wires but instead may be directly removed, thus rendering the connector more suitable for use in cramped spaces and where the several wires spread out in various directions.

15 From the foregoing it will be seen that multiple connectors made in accordance with the present invention are well adapted to attain the ends and objects hereinbefore set forth and to be economically manufactured since the combinations are 20 suited to common production methods and are susceptible to a wide latitude of variations as may be desirable in adapting the invention to different applications.

As various additional embodiments may be 25 made of the above invention and as changes might be made in the embodiments above set forth, it is to be understood that all matter hereinbefore set forth or shown in the accompanying drawings is to be interpreted as illustrative and 30 not in a limiting sense.

I claim:

1. A multiple connector comprising a plurality of connector blades arranged in closely spaced relationship along parallel axes and each having 35 a counterpart engaging clip near one end extending from one edge portion of the blade, and block means supporting said blades in said spaced relationship; said block means comprising intermediate slotted portions in each slot of which an 40 intermediate portion of a blade is disposed, said block means further comprising marginal portions provided with recesses, each recess being associated in communication with a slot of said slotted portions, and each recess presenting a 45 surface in closely spaced juxtaposition with respect to said one edge portion of the blade disposed in the slot associated with such recess.

2. In apparatus of the character described, 50 block means of insulating material, and electrical connector means fitted within said block means and projecting outwardly therefrom; said connector means being of the knife-disconnect type and having a blade with a clip near the outer end thereof, said means including a counterpart-clip-abutment portion spaced inwardly from said clip by an amount substantially equal to the width of said clip, whereby a counterpart knife-disconnect connector may be engaged with said connector means with the forward edge of the clip 55 of the counterpart connector camming against said abutment portion to jam the two clips into solid, highly conductive electrical engagement, and said block means including removable wall-defining means in spaced juxtaposition with respect to said connector blade means, the spacing between said wall-defining means and said blade means being less than the amount of clearance necessary to accomplish a knife-disconnect movement of a counterpart connector.

3. The invention of claim 2 wherein said abutment portion is formed by a part of said connector means.

4. The invention of claim 2 wherein said electrical connector means is attached at a region 70 remote from said clip to an electrical conductor.

5. The invention of claim 2 wherein said electrical connector means includes a plurality of projecting blades each provided with a clip.

6. The invention of claim 2 wherein said electrical connector means removably fits into a slot-like passageway within said block means.

JAMES C. MACY.
